UNITED STATES PATENT OFFICE.

FRANK M. BASHELIER, OF JENKINTOWN, PENNSYLVANIA.

DESIGN FOR A PRINTER'S CABINET.

49,294.

Specification for Design.

Patented July 4, 1916.

Application filed September 8, 1910. Serial No. 581,100. Term of patent 14 years.

To all whom it may concern:

Be it known that I, FRANK M. BASHELIER, a citizen of the United States, residing at Jenkintown, in the county of Montgomery and State of Pennsylvania, have invented a new, original, and ornamental Design for Printers' Cabinets, of which the following is a specification.

My said design is shown in the accompanying drawing which is a perspective view showing a printer's cabinet of the design in question.

What I claim is:

The ornamental design for a printer's cabinet as herein shown.

In witness whereof, I, have hereunto set my hand and seal at Washington, District of Columbia this 20th day of August, A. D. nineteen hundred and ten.

FRANK M. BASHELIER. [L. S.]
